(57) CLAIM

The ornamental design for a dog head covering, as shown and described.

DESCRIPTION

FIG. 1 is a side elevational view of a dog head covering showing my new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a front perspective view thereof shown in use.

The dog depicted by broken lines in FIG. 6 has been shown for the purpose of illustrating environment that forms no part of the claimed design.
